UNITED STATES PATENT OFFICE.

SYLVESTER F. HARTLEY, OF GOVERNEUR, NEW YORK, ASSIGNOR TO THE ST. LAWRENCE MANUFACTURING COMPANY, OF SAME PLACE.

LAND-ROLLER.

SPECIFICATION forming part of Letters Patent No. 380,033, dated March 27, 1883.

Application filed June 7, 1886. Serial No. 204,367. (No model.)

To all whom it may concern:

Be it known that I, SYLVESTER F. HARTLEY, a citizen of the United States, residing at Gouverneur, in the county of St. Lawrence 5 and State of New York, have invented certain new and useful Improvements in Land-Rollers, of which the following is a specification, reference being had therein to the accompanying drawings.

10 Figure 1 is a front elevation of my improved roller. Fig. 2 is an end elevation. Fig. 3 is a partial vertical section on line $x-x$, Fig. 2, looking in the direction of the arrow 1. Figs. 4, 4^a, and 4^b are detached views showing modifications. Fig. 5 is a vertical section on line $y-y$, Fig. 4, looking in the direction of the arrow 2, Fig. 4. Figs. 6 and 7 show a modification of 15 one of the bearing-boxes.

The invention relates to certain novel features of construction and combination, which 20 will be specifically pointed out in the claims.

A A are the front and rear sides of the box. B is the tongue. C C are ends of the box and are extended down below the body of the box 25 to form hangers for the roller-sections. These parts A A C C constitute a frame, to which there are attached bearings for the main axle, on which the drum-sections are mounted, as will be hereinafter explained.

30 The extreme lower end of each hanger is recessed, so as to straddle and fit closely the three flat right-angled sides of a bearing, E E'. (See Figs. 2 and 3.) The hanger is also provided with a narrow throat, b, extending from the 35 bearing upward, say, half the length of the hanger. The squared or right-angled part of the bearing is provided upon at least three of its sides with flanges or lips e e', which overlap and engage with opposite sides of the 40 hanger.

d is a bolt seated in the lower forked end of the hanger below the bearing, and serves to grip or clamp the hanger upon the opposite vertical faces of the bearing.

45 As will be readily understood, the throat b performs the double function of facilitating the desired clamping of the hanger to the box and of increasing the elasticity of the hanger, whereby the bearings can conform to the

irregular movements of the axle D without 50 serious cramping of the parts.

F is the seat.

G H H are drum-sections, of which the section G may, when desired, be keyed to the axle; but I prefer that the outer sections should 55 run loosely on the axle, in order to facilitate turning the roller in various directions, as may be required, without necessitating that either of the outer sections, H H, should slide over the ground and to provide a uniform motion 60 of seeder on an irregular course.

It will be noticed that the central section, G, has a length about equal to that of both the sections H H. The object of this is to prevent undue deflection of the axle, I having found 65 that with the ordinary construction of a roller of this length in two drum-sections, whereby there is a bearing and consequent thrust upon the center of the axle, there is in actual service apt to be so serious a deflection of the axle as 70 to rapidly cut out the bearings; but this is obviated by using a relatively long drum-section in the center with two relatively short sections at its ends. This defect is largely overcome by making the roller in three drum- 75 sections of equal length; but I prefer to make the middle one the longer.

As shown in Figs. 1, 2, and 3, each drum-section has a groove near its ends, which may be conveniently rolled in after the ends of the sheet 80 or sheets have been riveted together. These grooves serve the double purpose of stiffening the shell and also of furnishing a support for the outer edges of the felly-sections I I, which may be made of wood or metal, and are mounted 85 on the outer ends of spokes i i, which at their inner ends are seated in hub L. These spokes are threaded at their outer ends and have nuts, whereby the felly-sections may be thrust out against the inner wall of the shell.

In order to spread the ends of the felly-sections apart, thus producing an additional tension upon the parts, I employ wedges J, mounted on the outer ends of intermediate spokes, K, with nuts on the spokes to force the 95 wedges between the adjacent ends of the felly-sections. (See particularly Figs. 2, 4, and 5.)

By an examination of Figs. 1 and 3 it will

be seen that although the ends of the drum run in close proximity to the hangers CC, they are prevented from contact therewith by reason of the engagement of the hubs of the drum-
 5 section with the inner faces of the axle-bear-
 ings, and of the fellies being forced against the inner surface of the shell so tightly that the ends of the shell, the fellies, and the hubs are maintained in substantially a uniform relation
 10 to the frame-work. Another advantage of using these wedges is this: I am enabled to use fellies of such length that when under satis-
 15 factory tension their ends are so far apart that water will readily pass between them, whereby the drum-sections are drained, it being fre-
 20 quently the case that water, either in the form of rain or snow, is driven between the spokes to the interior of the drum during a storm, and would seriously rot the fellies were there no outlets for it.

In Figs. 4 and 5 the grooving of the shell differs somewhat from that shown in Figs. 1, 2, and 3, in that it bulges outward, thus forming ribs or beads on the outer surfaces of the drums. This construction has perhaps some advantages over the other, in that the outer edges of the fellies are seated in grooves instead of straddling ridges, so that there is no tendency to split the fellies, but rather a tendency to prevent them from being split. Again, it is probably easier to round the outer edges of the fellies than to groove them; in fact, if the grooves in the shell are wide enough, it may not be necessary to even round the outer edges of the fellies.

In Figs. 6 and 7 I have shown a somewhat different form of bearing, in which the tubular part or cylindrical-shaped part M has an upward-projecting flange, m, secured to the lower ends of the hangers C by bolts n n and nuts.

I am aware that in wagon-wheels wedges have been inserted between the ends of adjacent fellies and combined with various devices for thrusting the wedges outward and thereby spreading apart the ends of the fellies; but such devices do not accomplish the same ends in wagon-wheels that they do when combined with the other parts which go to make up a land-roller. For instance, one desirable function of these wedges in a land-roller is to keep the ends of the fellies spread apart, and thereby provide openings for the escape of water from the interior of the drum. Then, again, in a land-roller there is always some kind of a frame in or upon which the central shaft is mounted, with a hanger or a frame-piece of some kind close by the ends of the shell at each end of the machine. Now it is apparent that if there were no means provided for keeping the fellies permanently in their proper relations to the shell, or shells, where more than one are used, there would be great liability of the end of the drum working out beyond the vertical plane of the fellies and into contact with the adjacent portion of the frame. This objectionable result is avoided

by the use of my invention, which renders it easy for the operator to keep the fellies forced tightly out against the shell at the ends of the drum, thus insuring that the shell shall not 70 work endwise relative to the fellies. None of these functions or results is incident to the use of wedges in combination with fellies in wagon-wheels, but are due to the presence of the shell in combination with the other parts 75 in a land-roller.

I do not wish to be limited to the exact construction shown of any of the parts, because many modifications will suggest themselves to those who are familiar with this class of machines without departing from the spirit of my invention.

I do not in this case claim any features except those which are specifically recited in the claims, reserving the right to claim all other 80 patentable subject-matter in another application which I propose to file as a division and make concurrent with this one.

What I claim is—

1. In a land-roller, the combination of a 90 supporting - frame, an axle mounted in the frame, a metal shell, fellie-sections inside either end of the shell, hubs at either end of the shell, spokes projecting from the hubs, and adjustable wedges adapted to spread apart the adjacent ends of the fellies, substantially as set forth.

2. In a land-roller, the combination of a shaft, a series of hubs mounted upon the shaft, the spokes, outward-adjustable fellies sup- 100 ported upon said hubs, and a sheet-metal cylinder supported upon and connecting said series of fellies and hubs, substantially as set forth.

3. In a land-roller, the combination of the 105 main frame, downward-projecting hangers, a shaft mounted at its ends in the hangers, hubs mounted on the shaft, spokes, fellies mounted on the ends of the spokes, a sheet-metal in- 110 closing-cylinder surrounding the fellies, and means for adjusting the fellies outward upon the spokes, substantially as set forth.

4. In a land-roller, the combination of the main frame, an axle mounted in the main frame, a series of hubs mounted loosely upon 115 the axle, spokes projecting outward from the hubs, fellies at the outer ends of the spokes, and a sheet-metal drum supported upon the fellies and connecting the series of hubs, substantially as set forth.

5. In a land-roller, the combination of the main frame, an axle mounted on the main frame, a series of hubs mounted loosely upon the axle, spokes projecting outward from the hubs, adjustable fellies at the ends of the 125 spokes, and the sheet-metal cylinder supported upon the fellies and connecting the series of hubs, substantially as set forth.

6. In a land-roller, a drum having a sheet- metal cylinder, in combination with fellies 130 having outer convex faces which feed the inner face of the cylinder and inner substantially

straight edges, an axle, hubs, and spokes, substantially as set forth.

7. In a land-roller, the combination of a drum having a sheet-metal cylinder, fellies 5 upon which said cylinder is supported, and interlocking projections between the cylinder and the fellies to prevent relative movement, substantially as set forth.

In testimony whereof I affix my signature in presence of two witnesses.

SYLVESTER F. HARTLEY.
